UNITED STATES PATENT OFFICE.

PAUL HAAG, OF CHICAGO, ILLINOIS, ASSIGNOR TO POPE MANUFACTURING COMPANY, OF JERSEY CITY, NEW JERSEY, A CORPORATION OF NEW JERSEY.

FRAME FOR BICYCLES.

SPECIFICATION forming part of Letters Patent No. 748,602, dated January 5, 1904.

Application filed August 1, 1903. Serial No. 167,831. (No model.)

To all whom it may concern:

Be it known that I, PAUL HAAG, a citizen of the United States, residing in the city of Chicago, county of Cook, State of Illinois, have invented certain new and useful Improvements in Frames for Bicycles, &c., of which the following is a specification, reference being had to the accompanying drawings, forming a part hereof.

10 This invention relates to frames for bicycles and other-like vehicles which are adapted to yield somewhat and so cushion the rider against undue shocks and vibrations resulting from the roughness of the road-bed over which the vehicle is propelled.

15 The invention is particularly concerned with the front fork, and has for its object to produce a spring-fork which shall yield sufficiently and yet shall be strong enough to endure all the conditions of ordinary use.

20 The invention will be more fully described hereinafter with reference to the accompanying drawings, in which it is illustrated, and in which—

25 Figure 1 is a front elevation, partly in vertical section, of a spring front fork constructed in accordance with the present invention. Fig. 2 is a view of the same, also in side elevation and partly in vertical section. Fig. 3 is a plan view with the fork-tube in section on the plane indicated by the line 3-3 of Fig. 1.

30 The crown *a* of the front fork may be constructed in any usual or desired manner, except as herein indicated, and may have the fork-tube *b* secured thereto in any usual manner. The crown is provided with rearwardly-projecting lugs *c*, one at each side and at the corresponding end of the crown, 35 and with downwardly-projecting lugs *d*, one at each side, but set in somewhat from the end of the crown to form a shoulder *e*, whereof each rearwardly-projecting lug forms an extension. Each member *f* of the front fork is independently pivoted upon the corresponding lug *d* and has at its upper end a rearwardly-extending lug *g* to coöperate with the rearwardly extending lug *e* of the crown and prevent flexing of the fork backward beyond the normal position.

Each member *f* of the fork is pivoted upon the outside of the corresponding lug *d* by a pivot-screw *h*, which is provided with a bushing *i* to form a bearing for the fork member and is threaded into a lug *d*, as at *k*, the end 55 of the screw projecting through the end of the lug *d* to receive a bushing or check-nut *l* and being double-locked by such check-nut and a check-stud *m*, which is threaded into the check-nut. A compression or main cushioning-spring *n* is applied to each fork member, being placed within a spring-case *o*, provided with a cap *p* and held by a headed bolt *q*, which extends downward through suitable enlarged apertures in the lugs *c* and 60 *g* and receives on its lower end below the spring-case a nut *r*. It is possible by means of the bolt *q* to adjust the tension of both springs so that the tension of the tube shall be the same and so that the fork sides *f* shall there- 65 by move in unison. Sufficient space is left between the top of the spring-case and the lug *g* to allow for proper compression of the spring *n*, the spring-case telescoping within the cap *p*, and so forming a tight envelop for 70 the spring.

75 It is found desirable, both for the comfort and the safety of the rider, to supplement the compression-spring *n* by auxiliary springs *s*, one spring *s* at each side being mounted 80 on the bushing or check-nut *l* and having the shorter end *t* engaged with the fork-crown, as by being entered in a hole drilled in the under side thereof, as clearly indicated in Figs. 1 and 2, while the longer arm *u* thereof 85 bears rearwardly against a stud *v*, fixed in the fork. These auxiliary springs supplement the action of the main compression-springs, being always under tension and making it unnecessary to maintain the springs *n* under a 90 considerable degree of compression when the fork sides are in normal position, besides contributing considerably to the comfort of the rider in preventing the transmission of vibrations to the saddle of the bicycle. 95

I claim as my invention—

1. A spring-fork for bicycles, &c., comprising a fork-crown having rearwardly and downwardly extended lugs, fork sides pivoted upon said downwardly-extended lugs respectively 100

and having rearwardly-extended lugs to coöperate with the rearwardly-extended lugs of the fork-crown and positively limit the rearward movement of the fork sides, and compression-springs coöperating with said rearwardly-extended lugs of the crown and fork sides to hold the fork sides in normal position with the rearwardly-extending lugs of the fork-crown and the fork sides in contact, substantially as described.

2. A spring-fork for bicycles, &c., comprising a fork-crown having rearwardly and downwardly extended lugs, fork sides pivoted upon said downwardly-extended lugs respectively and having rearwardly-extended lugs to coöperate with the rearwardly-extended lugs of the fork-crown and positively limit the rearward movement of the fork sides, compression-springs coöperating with said rearwardly-extended lugs respectively, spring-cases supporting said springs, and bolts extended through said rearwardly-extended lugs and engaging said spring-cases whereby the fork sides are held in normal position with the rearwardly-extending lugs of the fork-crown and the fork sides in contact, substantially as described.

3. A spring-fork for bicycles, &c., comprising a fork-crown having rearwardly and downwardly extended lugs, fork sides pivoted upon said downwardly-extended lugs respectively and having rearwardly-extended lugs to coöperate with the rearwardly-extended lugs of

the fork-crown and positively limit the rearward movement of the fork sides, compression-springs coöperating with said rearwardly-extended lugs to hold the fork sides in normal position with the rearwardly-extending lugs of the fork-crown and the fork sides in contact, and auxiliary springs mounted upon the pivots of the fork sides respectively and engaging the crown and fork sides at their opposite ends, substantially as described.

4. A spring-fork for bicycles, &c., comprising a fork-crown having rearwardly and downwardly extended lugs, fork sides pivoted upon said downwardly-extended lugs respectively and having rearwardly-extended lugs to coöperate with the rearwardly-extended lugs of the fork-crown, pivot-screws for said fork sides engaged with said downwardly-extended lugs, check-nuts or bushings engaging the inner ends of said pivot-screws, compression-springs coöperating with said rearwardly-extended lugs, and auxiliary springs mounted upon said bushings or check-nuts and engaged at their opposite ends with the crown and fork sides, substantially as described.

This specification signed and witnessed this 7th day of July, A. D. 1903.

PAUL HAAG.
